(57) CLAIM

The ornamental design for a medical garment bottom as shown and described.

DESCRIPTION

FIG. 1 is a perspective view of a medical garment bottom showing the new design.

FIG. 2 is a front view of the medical garment bottom.

FIG. 3 is a rear view of the medical garment bottom.

FIG. 4 is a left side view of the medical garment bottom.

FIG. 5 is a right side view of the medical garment bottom.

FIG. 6 is a top view of the medical garment bottom.

FIG. 7 is a bottom view of the medical garment bottom.

FIG. 8 is a perspective view of the medical garment bottom.

FIG. 9 is a front view of the medical garment bottom.

FIG. 10 is a rear view of the medical garment bottom.

FIG. 11 is a left side view of the medical garment bottom.

FIG. 12 is a right side view of the medical garment bottom.

FIG. 13 is a top view of the medical garment bottom.

FIG. 14 is a bottom view of the medical garment bottom; and,

FIG. 15 is a left side view showing a pocket without the front panel.

The broken lines in FIG. 15 depict enlarged areas and form no part of the claimed design. The broken lines within the square pocket in FIG. 15 form no part of the claimed design.

1 Claim, 15 Drawing Sheets
